UNITED STATES PATENT OFFICE

2,199,493

CONTINUOUS WIRE-DRAWING MACHINE

Charles D. Johnson, Worcester, Mass., assignor
to Johnson Steel & Wire Company, Inc.,
Worcester, Mass., a corporation of Massachusetts

Application November 5, 1938, Serial No. 239,107

7 Claims. (Cl. 205—14)

This invention relates to wire-drawing machines of that type in which the drawing drum has associated therewith an element adapted to contain dry lubricant, and means are provided for directing the dry lubricant on to the wire and on to the wire-receiving surface of the drum as the wire is delivered to and wound thereon.

A device of this type is illustrated in my Patent 1,948,664, dated February 27, 1934.

In the device illustrated in said patent, the drawing drum has rigid therewith a dry lubricant-containing flange situated directly below the wire-receiving surface of the drum and which carries a quantity of lubricant in dry powder form, and a plow element is employed which acts on the dry lubricant thereby to direct or plow the dry lubricant against the wire-receiving surface of the drum at the point where the wire is delivered thereto. Both the wire and the drum thus receive sufficient lubrication so that the wire will not be injured by any slippage which occurs between the wire and the drum, and as the wire leaves the drum to be led through the next die said wire will carry sufficient dry lubricant to give it proper lubrication.

The machine illustrated in said patent functions satisfactorily as long as the drum is rotating at a moderate speed, but if the speed of the drum is increased beyond a certain point, the centrifugal force tends to throw the dry lubricant off from the flange, and, therefore, the speed of operation of a device such as shown in said Patent 1,948,664, is limited to the speed at which the drum can be rotated without having the dry lubricant thrown off from the lubricant-containing flange by centrifugal force.

In my present invention, I have provided a novel construction by which the speed of rotation of the drawing drum can be greatly increased without subjecting the dry lubricant to sufficient centrifugal action to discharge it from the drum.

I accomplish this end by making the lubricant-containing member separate from the drum and mounting it coaxially therewith, and by providing means to rotate the lubricant-containing member independently from the drum.

With this construction, it is possible to rotate the drum at an increased speed thereby increasing the speed of production of the wire-drawing machine, and at the same time to rotate the lubricant-containing member at a slow enough speed so that the dry lubricant will not be thrown off therefrom by centrifugal action.

In order to illustrate my invention, I have

shown in the drawings a selected embodiment thereof which will now be described after which the novel features will be pointed out in the appended claims.

In the drawings:

Fig. 1 is a section on the line 1—1, Fig. 2;

Fig. 2 is a plan view of one of the drawing drums of a continuous wire-drawing machine showing the dry lubricant containing member associated therewith;

Fig. 3 is a section on the line 3—3, Fig. 2;

Fig. 4 is a fragmentary sectional view showing the plow element for plowing the lubricant against the drawing drum;

Fig. 5 is a plan view illustrating a continuous wire-drawing machine having my improvements embodied therein;

Fig. 6 is a fragmentary sectional view illustrating suitable means for rotating the lubricant-containing members.

Referring first to Fig. 5, there is shown therein a series of wire-drawing drums 1 of a continuous wire-drawing machine, and at 2 are indicated the dies through which the wire 21 is drawn.

As the wire is delivered from any die 2, it passes around a cooling roll 3 and then passes or is delivered to the next drawing drum 1, said wire being wound around the drum a sufficient number of times to provide the necessary traction to draw the wire through the die. From the drum 1 the wire passes to a second die, then around a second cooling drum, and then to the third drawing drum around which it makes several turns to provide the necessary traction, and so on.

After having been drawn through the entire series of dies, the completed wire is wound on an accumulating drum 4.

Each drawing drum 1 is fast on the upper end of a vertical shaft 6, and the shafts 6 for the various drums are driven from a driving shaft 7 which extends longitudinally of the machine, the driving connection between the driving shaft 7 and each drum shaft 6 being in the form of meshing bevel gears 8 and 9, one of which is fast on the driving shaft, and the other of which is fast on the drum shaft 6.

The parts thus far described are such as may be found in various continuous wire-drawing machines.

Associated with each wire-drawing drum 1 is a rotary dry lubricant-containing member 10 which has a coaxial relation with the drawing drum but which is mounted to rotate independently from said drum. Each dry lubricant-containing element 10 is provided with an annular

chamber or trough 11 situated exterior to the drum and directly below the wire-receiving surface 12 of the drum, this chamber being adapted to contain a suitable dry lubricant 13 which may 5 conveniently be in powdered form.

I have stated above that the lubricant-carrying member 10 is separate from the drum and is adapted to be separately rotated. This lubricant-carrying member 10 is shown as carried by 10 a sleeve member 14 through which the shaft 6 extends and in which said shaft has a bearing, the sleeve 14 being supported in the frame or table 15 through the medium of suitable bearings 16.

15 The upper end of the lubricant containing member 10 is shown as being recessed at 17, and a ball bearing 18 located in the recess serves to provide a suitable bearing or support for the upper end of the drum shaft 6.

20 The sleeve 14 is provided with a gear 19 which meshes with and is driven by driving gear 20, said driving gear 20 providing means for rotating the lubricant-containing member 10 which is separate from the means for rotating the drum 1.

25 The lubricant-containing member 10 has associated therewith means which becomes operative when said member is rotating to plow the dry lubricant 13 in the trough 11 on to the wire-receiving surface 12 of the drum and on 30 to the wire at the point where the wire is delivered to the drum.

This means is in the form of a plow or deflector 22, the lower portion 23 of which occupies the trough 11 and the upper portion 24 of which 35 extends above the portion of the drum on which the wire is received. The upper portion 24 of the plow is also shown as curved inwardly toward the drum.

40 This plow is stationarily mounted and it is herein shown as carried by an arm 25 mounted on the upper end of a post 26 rising from the table or frame 15.

The plow 22 has a portion 27 lying against the 45 inside of the outer wall 28 of the trough 11 and a portion 29 extending across said trough.

45 As the lubricant-containing member 10 rotates in the direction of the arrow a, Fig. 2, the dry lubricant 13 in the trough 11 will pile against the stationary plow 22 and will be diverted or 50 directed thereby against the wire-receiving surface 12 of the drum and against the wire 21 as it is wound thereon, as shown at 30 in Figs. 1 and 2, thereby supplying both the wire-receiving surface and wire with the necessary lubricant.

55 Since the lubricant-containing member 10 can be rotated independently of the drum 1, it is possible to speed up the rotation of the drum, thus increasing the output of the machine, and at the same time to rotate the lubricant-containing 60 member 10 at a sufficiently slow speed so that the dry lubricant will not be thrown out of the trough by the centrifugal action.

65 The lubricant-containing member 10 is shown as having a second trough 31 outside of the trough 11, this trough 31 serving to catch and retain any dry lubricant which spills over the wall 28 of the trough 11.

I have also shown a second plow 32 similar to 70 the plow 22 but which operates in the outer trough 31, this plow 32 serving to plow the lubricant 13 which accumulates in the trough 31 back into the inner trough 11, as shown in Figs. 2 and 3.

75 The plow 32 is shown as carried by an arm 33

which is mounted on a post 34 rising from the table or frame 15.

While it is within the invention to provide separate means for rotating the various lubricant-containing members 10 of a continuous wire-drawing machine, yet it will be convenient to provide suitable gearing connecting the sleeves 14 of the various lubricant-containing members 10 so that they may be all operated from a single driving member. 10

Such a construction is shown fragmentarily in Fig. 6 wherein each sleeve 14 has a gear 19 thereon and the gears 19 of adjacent drums are connected by an intermediate gear 40. With this construction a single driving member 20 will 15 suffice for rotating all of the lubricant-containing members 10.

While I have illustrated a selected embodiment of my invention, I do not wish to be limited to the constructional features shown. 20

I claim:

1. A wire-drawing apparatus having a drawing die, a drawing drum provided with a wire-receiving surface on which wire is wound after passing through the die, a rotary lubricant-carrying member coaxial with and encircling the drum and adapted to contain a dry lubricant, means to rotate the drum, other means to rotate the lubricant-carrying member at a different speed from that of the drum, and means cooperating with the lubricant-carrying member and rendered operative by the rotation thereof to deliver the dry lubricant carried thereby against the wire-receiving surface of the drum. 25

2. A continuous wire-drawing apparatus having a plurality of drawing drums around which the wire to be drawn passes successively, a drawing die for each drawing drum, an annular lubricant-carrying member coaxial with the encircling each drum and adapted to contain dry 40 lubricant, means to rotate the drums, means to rotate each lubricant-carrying member at a slower speed than that at which the corresponding drum rotates, and means cooperating with each lubricant-carrying member to deliver the dry 45 lubricant carried thereby against the wire-receiving surface of the drum as said member rotates.

3. A continuous wire-drawing apparatus having a plurality of drawing drums around which 50 the wire to be drawn passes successively, a drawing die for each drawing drum, an annular lubricant-carrying member coaxial with and encircling each drum and adapted to contain dry lubricant, means to rotate the drums, means to 55 rotate each lubricant-carrying member at a slower speed than that at which the corresponding drum rotates, and a plow element cooperating with each lubricant-carrying member to deliver the dry 60 lubricant carried thereby against the wire-receiving surface of the drum as said member rotates.

4. A continuous wire-drawing apparatus having a plurality of drawing drums around which the wire to be drawn passes successively, a drawing die for each drawing drum, an annular 65 trough-shaped element coaxial with and encircling each drum, each trough-shaped element adapted to carry dry lubricant, means to rotate the drums, means to rotate each trough-shaped 70 element at a speed slower than the corresponding drum, and a plow element cooperating with each trough-shaped element to deliver the dry lubricant carried thereby against the wire-receiving surface of the drum as said element rotates. 75

5. A continuous wire-drawing apparatus having a plurality of drawing drums around which the wire to be drawn passes successively, a drawing die for each drum, an annular lubricant-carrying member coaxial with and encircling each drum, each member having two concentric open channels, each adapted to contain a dry lubricant, means to rotate the drum, means to rotate each lubricant-carrying member at a slower speed than 10 that of the corresponding drum, a plow element operating within the inner channel to deliver the dry lubricant therein against the wire-receiving surface of the drum as said member rotates, and a second plow operating in the outer channel and 15 operating during rotation of said member to plow the dry lubricant in the outer channel into the inner channel.

6. A wire-drawing apparatus comprising a drawing die, a rotary drum having a wire-receiving surface from which the wire is delivered to the die, means to draw the wire through the die, a rotary lubricant-carrying member adapted to contain dry lubricant, said member being coaxial with the drum and encircling the latter and also 20 mounted for rotation independently of the drum, means to rotate the drum, thereby to deliver the 25

wire to the die, other means to rotate the lubricant-carrying member at a slower speed than that of the drum, and means cooperating with the lubricant-carrying member and rendered operative by the rotation thereof to deliver the dry 5 lubricant carried thereby against the wire-receiving surface of the drum and the wire wound thereon.

7. A wire-drawing apparatus comprising a drawing die, a rotary drum having a wire-receiving surface from which the wire is delivered to the die, means to draw the wire through the die, an annular trough shaped element coaxial with and encircling the drum and adapted to carry dry lubricant, said trough-shaped element being 10 mounted for rotation independently of the drum, means to rotate the drum, thereby to deliver wire to the die, other means to rotate the trough-shaped element at a slower speed than that of the drum, and a plow element cooperating with 15 the trough-shaped element and operating to deliver the dry lubricant carried thereby against the wire-receiving surface of the drum as said element rotates. 20
